(57) **CLAIM**

I claim the ornamental design for an electrical compartmented device for keeping cold foods chilled, as shown and described.

DESCRIPTION

FIG. 1 is a perspective view of an electrical compartmented device for keeping cold foods chilled showing my new design;

FIG. 2 is a side elevational view thereof, the elevational view of the opposing side being a mirror image thereof;

FIG. 3 is an end elevational view thereof;

FIG. 4 is an elevational view of the opposing end thereof;

FIG. 5 is a top plan view thereof; and,

FIG. 6 is a bottom plan view thereof.

1 Claim, 3 Drawing Sheets

FIG. 1.

FIG. 2.

FIG. 3.

FIG. 4.

FIG. 5.

FIG. 6.
